ATTORNEY

UNITED STATES PATENT OFFICE

WILLIAM H. THOMPSON, OF BERKELEY, CALIFORNIA

GAS-COMPRESSOR UNIT

Application filed January 6, 1928. Serial No. 244,904.

My invention relates to an apparatus for liquefying a gas by compression and cooling, and particularly to a unit adapted for liquefying and circulating a normally gaseous refrigerant in refrigeration apparatus.

An object of the invention is to provide a condenser unit of the character described in which the gas compressing and cooling portions are unitarily associated in a particularly compact manner for removal together without necessitating a removal of the gas therefrom.

Another object of the invention is to provide a condenser unit of the worm type in which the worm and pump mechanism are immersed in a common cooling bath.

A further object of the invention is to provide in the unit particularly positive and efficient structural means for preventing leakage of the refrigerant therefrom.

A still further object of the invention is to provide in the unit an improved and particularly efficient gas compressing means.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings,

Figure 1 is a plan view of apparatus embodying the invention.

Figure 2 is a side view of the apparatus taken on the line 2-2 in Figure 1, and with portions of the structure broken away.

Figure 3 is a sectional view on the line 3-3 in Figure 2.

Figure 4 is a fragmentary view taken on the line 4-4 in Figure 2.

In the present embodiment of the invention, the condenser unit 6 of my invention is mounted on a base 7 formed to provide at different ends thereof an upwardly opening cavity 8 and a support for an actuating means such as an electric motor 9. The cavity 8 is

here shown of generally rectangular outline and a top closure member 11 is provided therefor, such closure member being arranged to be fixedly mounted on the cavity walls 12 by means of bolts 13. Upper and lower conduits 14 and 16 respectively are provided, each extending through a wall 12 of the cavity, it being noted that the conduits 14 and 16 are arranged to respectively provide outlet and inlet passages for the cavity for effecting a circulation of a suitable cooling fluid therethrough. If the cooling fluid is to be circulated under pressure, the cavity member 11 would, of course, provide a fluid-tight closure for the cavity. Preferably, and as shown, the base 7 is provided with a plurality of springs 17 at the under side thereof, such springs serving to provide vibration absorbing supporting feet for the apparatus.

It will now be noted that the member 11, besides serving as a closure for the cooling cavity 8, provides as integral parts thereof various frame elements of the unit 6 and a support for the complete unit assembly. Formed in the member 11 is a cylinder 18 having its axis vertical and having disposed therein a reciprocable piston 19. The cylinder 18, it will be noted, extends generally transversely through the member 11 and terminates in a crank case 20 at the lower end thereof, and the upper, or head, end of the cylinder is arranged to be closed by a head 21 removably secured to the cylinder as by stud bolts 22. A discharge passage for the cylinder is provided in the head 21 and such passage is provided with a suitable check valve. As herewith particularly shown, a passage 23 is provided in the head 21, such passage extending therethrough axially of the cylinder and having operatively disposed at the cylinder end thereof a lift valve 24 arranged to be opened by the discharge pressure of the pump.

For cooling a gas after it has been discharged under pressure from the cylinder 18, a coil, or worm, 26, is provided, said coil being mounted on the under, or cavity, side of the member 11. The convolutions of the coil, it will be noted, follow generally along the side walls of the cavity 8 and slope generally

downwardly from the inlet end 27 of the coil which is fixed to the member 11. The upper and major part of the coil is formed of tubing of relatively large diameter, while the lowermost coil portion 28 is formed of tubing of relatively small diameter to provide a sump for the reception of the liquefied gas—in this manner, a maximum cooling radiation is permitted and a minimum amount of refrigerant is required for charging the apparatus. A discharge pipe 29 for the condensed gas leads upwardly from the coil portion 28 through the member 11 to a discharge valve 31 mounted on the outer side of the member, whence it is arranged to be delivered through a conduit 32 to the expansion valve of a refrigerator (not shown).

Means are provided for connecting the coil end 27 with the passage 23, but since, as hereinbefore indicated, it is a primary object of the present invention to provide a unit which is particularly compact, the necessary connections are made within the member 11. Accordingly, and as shown, a passage 33 is provided through the member 11, such passage extending from a point in the seat of the head 21 to the point of connection of the coil end 27 to the member. A passage 34 is provided in the head 21 for connecting the inlet end of the passage 33 with an intermediate point of the passage 23 of the head. As here shown, the outer end of the passage 23 is arranged to be closed by means of a screw plug 36, such plug being provided with an axially directed boss 37 longitudinally perforated to receive the stem of the valve 24 for guiding the same. In this manner, the connections between the cylinder and coil are entirely concealed and form an integral part of the structure.

Journalled in the lower side of the member 11 to extend horizontally therefrom in alignment with the shaft 38 of the motor 9 is a drive shaft 39, said latter shaft being releasably secured to the shaft 38 by means of a suitable coupling 41, and having provided adjacent the inner end thereof a worm screw 42. Also journalled at the under side of the member 11 is a crank shaft 43, said shaft extending from the crank case 20 radially of the cylinder axis through a crank case wall 44 and being disposed transversely of the shaft 39, in non-intersecting relation therewith. A worm gear 46 is provided on the shaft 43 for engagement with the worm screw 42, while mounted on the shaft 46 within the crank case 20 is a crankpin 47, the latter being connected to the piston 19 by means of a connecting rod 48. In this manner, an operative connection between the motor and pump is provided substantially entirely within the cavity 8.

It will now be noted that the crank case 20 is arranged to contain oil in the lower portion thereof for effecting the lubrication of the connections of the connecting rod 48 with the

piston and crank shaft and that the geared connections between the drive shaft and crank shaft are also arranged to be lubricated with oil. Accordingly, and as here shown, the member 11 is formed to provide a suitably shaped gear case 49 about the worm screw and worm gear. The crank case 20 and gear case 49, it will be noted, have the wall 44 in common between them, and the crank shaft 43 is journalled in the wall 44 and the opposite end wall 51 of the gear case. Preferably, and as shown, the ball-bearings 52 and 53 are provided respectively in the walls 44 and 51 for supporting the crank shaft whereby friction effects may be minimized. Furthermore, the use of ball bearings in the wall 44 permits a flow of oil between the crank case 20 and gear case 49, it being noted that the bottoms of the crank case and gear case are semi-cylindrical and are desirably on a level, or nearly so, as shown. Preferably, the member 11 is perforated above the gear case to provide a filler opening 54 for placing lubricant in the gear case, and a removable screw plug 56 is provided for the opening 54. It will be clear that the crank case and gear case co-operate to provide in effect a single chamber for lubricant for the operative connections for the pump and that this chamber extends well toward the bottom of the cavity 8 with the convolutions of the coil 26 about it. In this manner, a cooling of the oil in the crank and gear cases is effected by the cooling medium in the cavity.

The drive shaft 39 is journalled in the opposite side walls 57 and 58 of the gear case 49. Suitable bearings for the shaft 39 are provided at the walls 57 and 58, and as here shown, such bearings are provided in removable bearing blocks 59 and 61 mounted in the respective walls. The bearing provided by the block 59 is in the form of a socket, while that provided in the block 61 comprises a cylindrical bore extending through the block. It will now be noted that the cylinder, crank case and gear case may together be thought of as a single cavity, and that the shaft opening through the block 61 is the only opening through which the gaseous refrigerant might escape from the apparatus. To prevent a possible escape of gas along the shaft 39 through the block 61, a special packing means is preferably provided in the block 61. As herewith particularly shown, the bearing block 61 is of rectangular outline and is hollow. At the points where the shaft 39 passes through the walls of the block, cylindrical bearing sleeves 62 and 63 are provided, such sleeves being integral with the box structure. The inner end of the sleeve 62, it is noted, extends through the wall 57 of the crank case and provides a direct bearing for the shaft 39, while the outer end of this sleeve and the sleeve 63 are respectively

arranged to provide inner and outer stuffing boxes for the shaft 39.

In the present embodiment of the invention, the shaft portion which extends through the stuffing boxes is reduced in size and the bore of the stuffing boxes is somewhat greater than that of the larger shaft portion, an annular shoulder 66 thus being defined in the bore of the sleeve 62 opposite the point of shaft reduction. A packing ring 67 is disposed about the reduced shaft portion and against the shoulder 66 and stuffing 68 is disposed against the said ring at the outer side thereof. Slidably mounted on the reduced shaft portion is a cylindrical sleeve member 69 arranged to slidably fit the bores of the stuffing boxes. The inner end of the sleeve 69 is formed to provide a packing gland for the stuffing in the inner stuffing box, while the outer end thereof is formed to provide the inner packing ring for the stuffing 68 in the outer stuffing box. Preferably, and as shown, the intermediate bore of the sleeve 69 is larger than the shaft portion therein and the sleeve is perforated opposite such portion to provide for admission of a lubricant thereto. The outer end of the stuffing box sleeve 63, it will now be noted, is externally threaded to receive a threaded ring 71 which 30 ring engages an outer gland 72 for the packing in the stuffing box 65. In this manner, a screwing up of the ring 71 simultaneously effects a pressure engagement of the glands of both stuffing boxes with the stuffing therein.

35 The block 61, it will now be noted, is arranged to be secured to the member 11 as by bolts 73 extending therethrough whereby it is removable from the base 7 with the member 11, it being noted that when the latter member is mounted on the base 7, the block 61 engages in a rectangular notch 74 provided in the cavity wall whereby the removal of the block 61 with the member 11 is permitted. The cavity of the block 61 is arranged to contain lubricating oil at least to a level above that of the stuffing boxes, whereby a truly gas-proof seal is provided against the leakage of refrigerant from the apparatus. For effecting the introduction of oil to the block cavity, aligned perforations are provided in the upper cavity wall and overlying portion of the member 11, closure for said perforations being provided by means of a screw plug 76 threadedly engaging the block 61. Two 55 sides and the bottom of the block 61, it will further be noted, are exposed within the cooling cavity 8 whereby the cooling of the oil therein is arranged to be effected.

60 The piston 19, it will now be noted, is in the general form of a hollow cylinder having a pressure operated valve 77 forming the central portion of the head end thereof. The valve 77 it will be noted is arranged to be closed during a working stroke of the piston, 65 and open during a suction stroke thereof. An

intake port 78 is provided in a side of the piston, such port being arranged to register for a considerable part of the piston stroke with a port 79 provided in the cylinder wall. An inlet conduit 81 for the port 79 is provided, such pipe connecting with the source of gas supply to be condensed by the apparatus. Thus when the apparatus is used for refrigeration purposes, the pipe 81 would be connected with the expansion chamber of a refrigerator (not shown). It will be clear that during each working stroke, while the gas is being forced under pressure ahead of the piston and through the cylinder outlet valve 24, gas from the pipe 81 will be filling the piston cavity at a pressure somewhat exceeding atmospheric, and that a return stroke of the piston will effect a transfer of the gas from the piston into the cylinder. In this manner, the cylinder is arranged to receive a charge of gas for compression in a particularly rapid manner and with a minimum power loss.

Metallic packing rings 82 are provided on the piston 19, and one or more of these rings are preferably formed to so wipe the cylinder walls during each intake stroke of the piston that a minimum amount of lubricating oil will be and remain on the cylinder wall portions with which the refrigerant gas contacts. And it will furthermore be clear that if any of the refrigerant does pass the piston, such escaped refrigerant will not be returned to the refrigerant circuit. In this manner, the possible contamination of the refrigerant with oil is reduced to a minimum.

It will be noted that if the compressing and cooling unit now described is to be removed for repair or replacement, the discharge valve 31 would be closed, the motor coupling 41 would be disengaged, and a loosening of the bolts 13 would then permit the removal of the unit 6 from its mounting on the base 7. In this manner, no gas escape is involved, and a replacement of a unit involves a minimum amount of work on the part of a mechanic, it being noted that this feature is an important element of the present invention.

In operating the device for circulating a refrigerant in refrigeration apparatus, a cooling medium such as water is set in circulation in the cavity 8 around the worm, crank case, gear case, and bearing block 61, and the motor is started. At each working stroke of the piston, the charge in the cylinder is expelled through the valve 24 into the connected passages 23, 34, 33 and so into the coil 26 where it gives up its heat of compression to the cooling medium and is thereby liquefied. The liquefied gas collects in the lower coil portion 28 and being still under pressure tends to flow from the worm through the pipe 29, valve 31, and conduit 32 at a rate permitted by the expansion valve (not shown) of the refrigerator. The gaseous refrigerant from

the expansion chamber (not shown) into which the expansion valve discharges is delivered through the conduit 81 to the cylinder port 79 and so into the piston cavity, whence it is discharged into the cylinder through the piston valve 77 upon a suction stroke of the piston. In this manner, it will be clear that refrigerant is arranged to be constantly circulated through the apparatus, and since substantially no leakage thereof is possible, a given charge of refrigerant will last indefinitely.

I claim:

1. In apparatus of the class described, a base member providing a cavity arranged for the circulation of a cooling fluid therethrough, a top wall for said cavity, a pump having cylinder and crankcase portions carried by said top wall, a crank shaft for said pump extending from said crankcase, a drive shaft extending into said cavity, means within said cavity operatively connecting the extending portions of said shafts, and a casing carried by said top wall enclosing said connecting means and the extending shaft portions, said casing and crank shaft being disposed in the fluid circulation space of said cavity.

2. In apparatus of the character described, a compressor of the reciprocating piston type having a vertically disposed cylinder, a drive shaft for said compressor, means operatively connecting said shaft and the compressor piston, a casing forming an extension of said cylinder and supportably enclosing said connecting means, a bearing provided in a wall of the casing having said drive shaft extending therethrough, said bearing including spaced stuffing boxes having the shaft portions between them arranged to be disposed in a lubricant at all time.

3. In apparatus of the character described, a gas compressor having a cylinder, a drive shaft therefor, means operatively connecting said compressor and shaft, a casing forming an extension of said cylinder and supportably enclosing said connecting means, a bearing block provided in a wall of the casing having said drive shaft extending therethrough, said block being hollow to provide a lubricant receiving cavity and providing spaced stuffing boxes in opposite walls thereof for the reception of said shaft.

In testimony whereof, I have hereunto set my hand at Oakland, California, this 22nd day of December, 1927.

WILLIAM H. THOMPSON.
